UNITED STATES PATENT OFFICE.

BENJAMIN P. LESLIE, OF NEW YORK, N. Y., ASSIGNOR TO NAETHING-LESLIE
TILING COMPANY, A CORPORATION OF NEW YORK.

DESIGN FOR TILE COVERING FOR FLOORS, WALLS, OR OTHER SURFACES.

SPECIFICATION forming part of Design No. 36,370, dated June 16, 1903.

Application filed February 7, 1903. Serial No. 142,417. Term of patent 14 years.

To all whom it may concern:

Be it known that I, BENJAMIN P. LESLIE, a citizen of the United States of America, and a resident of the borough of Brooklyn, county 5 of Kings, city and State of New York, have invented a new, original, and ornamental Design for Tile Covering for Floors, Walls, or other Surfaces, shown in the accompanying drawing, which illustrates by a view in plan 10 a tiled surface embodying my design.

What I claim as new is—

The ornamental design for tile covering for floors, walls, or other surfaces, as shown.

In testimony whereof I have signed my name to this specification in the presence of 15 two subscribing witnesses.

BENJAMIN P. LESLIE.
